W. J. BRADWELL

AUTOMATIC BOBBIN RELEASE

Filed June 8, 1926

Patented Dec. 21, 1926.

1,611,509

UNITED STATES PATENT OFFICE.

WILLIAM JOSEPH BRADWELL, OF CHARLESTON, SOUTH CAROLINA, ASSIGNOR OF ONE-HALF TO CHRISTOPHER F. HOTTINGER, JR., OF CHARLESTON, SOUTH CAROLINA.

AUTOMATIC BOBBIN RELEASE.

Application filed June 8, 1926. Serial No. 114,541.

This invention relates to automatic bobbin releases especially adapted for use in connection with yarn and thread spooling machines.

5 Briefly stated, an important object of this invention is to provide an automatic bobbin stop by means of which the driving connection between the bobbin and the spindle is broken when a predetermined amount of 10 thread, yarn, or the like, has been wound upon the bobbin so that the winding of additional thread, yarn, or the like, on the spool is avoided.

Another and equally important object of 15 the invention is to provide an automatic bobbin stop which may be easily adjusted for various diameter bobbins and which may be applied without the exercise of unusual skill to existing machines.

20 A further object of the invention is to provide an automatic bobbin stop which is of highly simplified construction, durable in use, and cheap to manufacture.

Other objects and advantages will be apparent during the course of the following description.

In the accompanying drawing forming a part of this application and in which like numerals are employed to designate like 30 parts throughout the same,

Figure 1 is a side elevation of the improved bobbin stop applied;

Figure 2 is a group perspective of the improved bobbin stop.

35 In the drawing, wherein for the purpose of illustration is shown a preferred embodiment of the invention, the numeral 5 designates a spindle which, as illustrated in Figure 1, may be tapered toward the upper end 40 thereof to support a bobbin or spool 6 upon which thread or yarn is wound. It is believed to be obvious that the weight of the bobbin 6 on the tapered spindle results in driving contact of the spindle with the bobbin and that when the bobbin is elevated the driving engagement between the bobbin and the spindle will be broken.

The invention forming the subject matter 50 of this application consists of a one-piece lever having a horizontal branch 7 and a forwardly tilted longitudinally curved branch 8, the branch 8 in addition to being curved longitudinally being curved transversely for contact by the thread wound upon the bobbin. Particular attention is directed to the

fact that the major portion of the branch 8 is on the same side of the axis of the pivot member 9 as is the approximately horizontal branch 7 so that the weight of the lever is principally at one side of the pivot point. 60 Therefore, the upper branch 8 will be normally tilted in the direction of the spool by force of gravity.

The horizontal branch 7 is provided adjacent the inner portion thereof with a rectangular ear 10 pivoted to the bifurcated upper end of a stem 11 as indicated at 9. By bifurcating the upper end of the stem 11 a slot is formed for the reception of the ear 10 and a pair of bracing members are provided at opposite sides of the ear by means of which the lever is caused to operate in approximately the same plane at all times. In other words, the lever is held against side swaying or tilting by the bracing members 70 at opposite sides of the ear 10.

To avoid excess swinging of the lever, the bottom of the slot in the upper portion of the lever 11 is in the path of travel of and is adapted to be engaged by the flat lower end 80 of the ear 10. This effectively limits the oscillation of the lever. It will be readily seen that unlimited freedom of the lever would permit the branch 8 to swing in and engage the thread long before the bobbin is full or 85 nearly full. Therefore, the branch 8 is in engagement with the thread for a very limited period.

The stem 11 is extended into the socket of a standard 14 and may be held in an adjusted position by means of a set screw 15. The stem 11 may be adjusted vertically or about its own axis.

The standard 14 is mounted on an elongated attaching plate 16 which in turn is 90 mounted upon a base plate 17. Particular attention is directed to the fact that the attaching plate 16 is provided with a slot 18 substantially longer than a lug 19 which it receives so that the attaching plate 16 may 100 be adjusted longitudinally of the base plate. The upstanding lug 19 which is also of elongated formation is provided with a threaded stem 20 for engagement by thumb screw 21 by means of which the attaching plate may 105 be securely held in place. When the attaching plate 16 is positioned on the base plate 17 the lug 19 will engage the side walls of the slot 18 and thereby effectively hold the attaching plate against turning.

One end portion of the base plate 17 is provided with an opening 26 for the reception of the shaft 5 and a hexagonal nut 27 or other suitable fastening device may be employed to secure the base plate to the machine as will be apparent.

With reference to the foregoing description taken in connection with the accompanying drawing it will be seen that the attachment provides a means whereby the thread on the spool forms a means whereby the bobbin is automatically released from driving engagement with the spindle when the diameter of the spool reaches a predetermined point. As previously stated, the thread on the bobbin will not engage the transversely curved portion of the lever until the diameter of the spool approaches the proper point. The release of the bobbin is accomplished without strain on the thread and to entirely detach the bobbin from the spindle it is merely necessary to swing the lever to its outer position so that the flange at the lower end of the spool will clear the upper branch 8. When the lever is swung to its outer extreme position it will remain in that position until again tilted inwardly. In other words, the bobbin may be either applied or removed without changing the adjustment of the machine and without inconvenience.

Having thus described the invention, what is claimed is:

1. An automatic bobbin release comprising a lever having a short horizontal branch and a long upwardly extending inclined branch curved transversely for engagement by the thread on a bobbin, said lever being provided with an attaching ear, and a support having a bifurcated upper end portion defining a slot receiving said ear and a pair of bracing members at opposite sides of the ear, the bottom wall of said slot being in the path of travel of and adapted to be engaged by the lower edge of the ear to limit the swinging movement of the lever in both directions.

2. An automatic bobbin release comprising a lever having a short horizontal branch and a long upwardly extending inclined branch curved transversely for engagement by the thread on a bobbin, said lever being provided with an attaching ear, a support having a bifurcated upper end portion defining a slot receiving said ear and a pair of bracing members at opposite sides of the ear, the bottom wall of said slot being in the path of travel of and adapted to be engaged by the lower edge of the ear to limit the swinging movement of the lever in both directions, and means whereby said support may be adjusted transversely and vertically.

3. An automatic bobbin release comprising a lever having a short horizontal branch

and a long upwardly extending inclined branch curved transversely for engagement by the thread on a bobbin, said lever being provided with an attaching ear, a support having a bifurcated upper end portion defining a slot receiving said ear and a pair of bracing members at opposite sides of the ear, the bottom wall of said slot being in the path of travel of and adapted to be engaged by the lower edge of the ear to limit the swinging movement of the lever in both directions, and means whereby said support may be adjusted transversely and vertically, said long branch of the lever being extended in the direction of the short branch of the lever.

4. An automatic bobbin release comprising a lever having long and short branches, the short branch being adapted to engage a bobbin and the long branch being extended over the short branch and being curved for engagement by the thread on a bobbin, an ear connected to the lever, a stem pivotally supporting the ear and having means to limit the swinging of the lever, and an adjustable support for said stem.

5. An automatic bobbin release comprising a lever having branches, one of which is adapted to engage a spindle and the other being adapted for engagement by the thread on a bobbin, an ear carried by the lever, a stem pivotally supporting the ear and having means co-operating with the ear to limit swinging of the lever, a standard having a socket adjustably receiving said stem, an attaching plate supporting the standard and having an elongated slot, and a base plate having an upstanding elongated lug received in said slot to hold the attaching plate against turning, and a screw extending upwardly from said lug and having a nut adapted to engage said attaching plate to hold the attaching plate in an adjusted position.

6. An automatic bobbin release comprising a lever having branches, one of which is adapted to engage a spindle and the other being adapted for engagement by the thread on a bobbin, an ear carried by the lever, a stem pivotally supporting the ear and having means co-operating with the ear to limit swinging of the lever, a standard having a socket adjustably receiving said stem, an attaching plate supporting the standard and having an elongated slot, a base plate having an upstanding elongated lug received in said slot to hold the attaching plate against turning, and a screw extending upwardly from said lug and having a nut adapted to engage said attaching plate to hold the attaching plate in an adjusted position, one end of said base plate being provided with an opening to receive a spindle.

In testimony whereof I affix my signature.
WILLIAM JOSEPH BRADWELL.
